PUSH KEY OPERATED HASP LOCK

Bohumil Polák, Prague, Czechoslovakia, assignor
to Koh-I-Noor, Spojene Kovoprumyslove
Zavody, narodni podnik, Prague, Czechoslo-
vakia

Application June 28, 1950, Serial No. 170,773
In Czechoslovakia July 12, 1949

3 Claims. (Cl. 70—74)

1

My invention relates to a hasp lock for trunks, portfolios or the like, which in its function and construction is more simple and more dependable than the known locks of that type and which moreover meets substantially better all requirements placed on the pleasant appearance of such locks.

The main feature of my new lock consists in a push key operated arresting device for a longitudinally slideable locking member which cooperates with the hasp of the lock. Said arresting device includes a particularly constructed ratchet or star wheel which upon each insertion of the push key is partially turned and alternately blocks and releases said longitudinally slideable locking member.

The objects of my invention, its construction and its mode of operation will be more fully understood from the following specification when read with the accompanying drawing in which one embodiment is illustrated.

In the drawing

Fig. 1 is a perspective view of the lock in its opened position,

Fig. 2 is a front view of the lock,

Fig. 3 is a sectional side view on an enlarged scale,

Fig. 4 is a perspective view of the ratchet or star wheel used in the lock mechanism, and

Figs. 5 and 6 show in front view said ratchet or star wheel and the parts cooperating therewith in unlocking and locking operations, respectively.

As shown in Fig. 1 my improved lock comprises a casing 2 which houses the lock mechanism and is secured to the body 1 of a trunk, briefcase or other receptacle, and a hasp 4 which is pivotally supported by a hasp plate 4' attached to the cover 3 of said receptacle. The hasp 4 is provided with a loop 5 which projects from the back thereof to enter the front opening 6 of the casing 2 and to receive the locking bolt or other locking member 7 when the hasp 4 is swung into the locking position shown in Fig. 3. A spring 9 holds the hasp 4 in open position as illustrated in Fig. 1 and forces the hasp into said open position as soon as the locking member 7 releases said loop 5.

The locking member or bolt 7 forms an integral part of a sliding member 8 located in the casing 2 and is held in locking position for engagement with the loop 5 by the loop spring 10 which rests with one arm in a shoulder 11 attached to the casing 2 and presses with its other arm against the locking bolt 7 or any other part of the sliding member 8. The locking bolt 7 has a beveled

2

front face so that the loop 5 when pressing thereagainst will temporarily push back said bolt 7 against the force of said spring 10 until the bolt 7 will be forced to engage the loop 5. The sliding member 8 projects from the casing 2 to form a finger piece 8' which may be manually actuated to move the bolt 7 out of engagement with the loop 5 when the lock is in unlocked position.

The sliding member 8, or the bolt or other locking member 7 integral therewith, is provided with a blocking pin or other arresting member 12 which projects therefrom and cooperates with a ratchet or star wheel 13. This wheel 13 is rotatably mounted on a pivot 14 within the casing 2 and is displaceable thereupon in axial direction. A helical spring 15, however, presses said star wheel 13 against the bottom wall of the casing 2.

As shown in Fig. 4 said ratchet or star wheel 13 has on its circular face a plurality of axially extending teeth 16 and between each pair of said teeth radial notches 21 which extend inwardly from the rim thereof. These radial notches 21 are adapted to receive the blocking pin or similar projection 12 when the same is aligned therewith and said teeth 16 are adapted to cooperate with the bit 17 of a push key 16 which may be introduced into the lock casing 2 through the coinciding lateral opening 22 and 23 on the casing 2 and the hasp 4, respectively. The end of said key 16 may be provided with a longitudinally incision 24 to cooperate with a fitting stationary arresting projection 24'. This projection 24' will permit the key 16 to be pushed with the lock only so far to effect a turning of the wheel 13 by one tooth 16 or pitch. The width of said incision 24 and projection 24' may be varied in different locks so that each lock will be operable only by its appropriate push key 16. A pawl 20 arranged in the casing 2 will prevent any incidental backward turning of the wheel 13.

The described hasp lock operates as follows:

The hasp 4 is pressed downward against the casing 2 from the position shown in Fig. 1 into the position shown in Fig. 3. The loop 5 upon entering the casing 2 through the opening 6 presses against the beveled front face of the bolt 7, presses the same back and receives the same under the action of the spring 10. The said backward movement of the bolt 7 is possible because the ratchet or star wheel 13 being in the unlocking position shown in Fig. 5 will permit the pin 12 to enter temporarily one of the radial notches 21 aligned therewith. When the key 16 is withdrawn from the casing 2 its bit 17 will slide along the inclined back face 19 of the preceding

tooth 18 and will raise the wheel 13 against the force of the spring 15 without turning the same as it is secured against backward movement by the pawl 28 which cooperates with the tooth 18. The lock will remain in unlocked position until the push key 16 is again introduced into the casing and the ratchet wheel 13 is turned by the bit 17 of the key 16 by one pitch into the position shown in Fig. 6. In this position the rim of the ratchet wheel 13 will block any displacement of the pin 12 thus preventing the locking bolt 7 from disengaging the loop 5. When thereafter the push key 16 is withdrawn from the casing 2 its bit 17 will again slide along the inclined back face 19 of the preceding tooth 18 and will raise the wheel 13 against the force of the spring 15 without turning the same as it is secured by the pawl 28. The lock will remain thereafter in locked position until the push key 16 is reintroduced into the casing 2 and the wheel 13 is turned by another pitch into the position shown in Fig. 5.

While I have shown and described one embodiment of my invention to illustrate the application of the principles thereof, it will be well understood that my invention may be otherwise embodied without departing from said principles.

What I claim as my invention is:

1. In a push key operated hasp lock of the type described including a longitudinally slidable locking member, an arresting device for said locking member, said arresting device comprising in combination a projection extending from said locking member; a ratchet or star wheel revolvable about an axis perpendicular to the direction of slide motion of said projection; ratchet teeth on the face of said wheel for cooperation with a bit on a push key upon its insertion into the lock for rotating said wheel; the said wheel arranged to block with its circular rim the slide motion of said projection and being mounted for slidable displacement in axial direction; a spring for holding said wheel in engagement with said bit; and said wheel having a plurality of notches radially extending inwardly from the rim thereof to receive said projection when aligned therewith and to thus allow displacement of said lock-

ing member, each one of said notches being arranged after each second ratchet tooth.

2. An arresting device according to claim 1, comprising a stop member for the push key to prevent the same from turning the ratchet wheel by more than one tooth upon each insertion of the key into the lock.

3. In a push key operated hasp lock of the type described including a longitudinally slidable locking member, an arresting device for said locking member, said arresting device comprising in combination a projection extending from said locking member; a ratchet or star wheel revolvable about an axis perpendicular to the direction of slide motion of said projection; ratchet teeth on the face of said wheel for cooperation with a bit on a push key upon its insertion into the lock for rotating said wheel; a pawl cooperating with said wheel to prevent its back turning upon withdrawal of said key from the lock; the said wheel arranged to block with its circular rim the slide motion of said projection and being mounted for slidable displacement in axial direction; a spring for holding said wheel in engagement with said bit; and said wheel having a plurality of notches radially extending inwardly from the rim thereof to receive said projection when aligned therewith and to thus permit displacement of said locking member, each one of said notches being arranged after each second ratchet tooth.

BOHUMIL POLÁK.
